GLOVE IRONING MACHINE

Teobaldo G. Boldizzoni, New York, N. Y.

Application May 29, 1945, Serial No. 596,456

17 Claims. (Cl. 223—57)

1

This invention relates to new and useful improvements in machines for pressing gloves, especially gloves having seamed fingers.

In my prior patent, No. 2,186,192, I have described a pressing machine in which gloves are mounted on rotating forms and are stripped therefrom by means of two continuously rotating belts. The two belts are movable with respect to one another during the cyclic operation of the machine to permit the insertion of a form between the two belts without mutilating the glove and the subsequent stripping of the glove from the form.

In another Patent 2,324,673, I have shown that the forms on which the gloves are mounted can be readily attached to and removed from a rotating support, whereby various types of gloves may be pressed by the machine without requiring extensive alterations and the intervention of skilled mechanics.

The object of the present invention is a mechanism for pressing the fingers of the gloves to smooth the seams thereof so that the hands may slip into the glove easily and comfortably.

Such pressing is now being done manually on relatively expensive gloves or not at all on relatively inexpensive gloves. These operations require a great deal of time and supervision. With my mechanism each glove will be uniformly pressed in an economical manner.

A further object of the invention is to achieve certain improvements in the machine described in my patents, and especially in Patent 2,324,673.

According to one of the features of the present invention, pressing members are provided which are inserted between the fingers of the form and moved parallel thereto to smooth the seams of the fingers separately.

More specifically, the form or forms on which the gloves are mounted when in operating position, are arranged with the fingers extending in a predetermined plane and the finger pressing members are arranged to move in a plane perpendicular to that predetermined plane to be inserted between the fingers.

According to a further feature of the invention, means are provided for heating the form or forms, or for heating the finger pressing members or both.

According to another feature of the invention, the form or forms are moved into and out of operative position, and the movement of form and finger pressing members are related to one another to occur in predetermined order to permit continuous pressing of a series of gloves.

2

In another embodiment of the invention, the form or forms are stationary and the finger pressing members are moved into and out of operating position under an operator's manual or pedal control.

These and other features of the invention will more clearly appear from the following detailed description of preferred embodiments of the present invention and the appended claims.

10 Fig. 1 is an elevated view of an automatic type machine permitting continuous finger pressing.

Fig. 2 is a partial plan view of this machine in assembled condition with certain parts shown in cross-section.

15 Figs. 3 and 4 are top plan and side views, respectively, of the finger pressing mechanism shown in Figs. 1 and 2.

Fig. 5 is an enlarged cross-section through a driving member for the finger pressing mechanism shown in Figs. 1 and 2.

20 Fig. 6 is a perspective view explaining the principal phases of finger pressing in a continuous type machine according to Figs. 1—5.

Fig. 7 is an elevated view of a semi-automatic type machine permitting finger pressing in discontinuous steps interrupted by manual operations.

Fig. 8 is a top view of the finger pressing mechanism of Fig. 7.

30 Fig. 9 is a top view of a cross-section along lines 9—9 in Fig. 7.

Referring first to Fig. 1, four glove forms, only three of which, 1, 1a and 1b, are shown, are fastened to a spider structure 2 by means of bolts 3. Structure 2 is mounted on and rotated by a hollow shaft 4 carried in brackets 5 and 6 on a table 7. As shaft 4 rotates, one form after the other is moved down through an opening in the table 7 between adjacent portions of two endless driven belts 8 and 9. Form 1b, with a glove mounted thereon, is shown as gripped between the two belts 8 and 9.

Belt 8 passes over a set of rollers comprising two small rollers 10 and 11 and an intermediate 45 large roller 12. Bearing against the outside surface of the belt 8 is a roller 13 supported in a frame 14 in which roller 11 is also supported. The frame 14 is carried in a framework 15 on which the table 7 is mounted. The belt 9 is similarly 50 mounted on a set consisting of two small rollers 16 and 17 and an intermediate large roller 18. The contacting portions of the two belts form a V at the bottom of which the large roller 12 is located. The belts contact with one another throughout their contiguous outer surfaces. By

mechanism to be presently described the portions of the belts extending between rollers 10, 12, 16 and 18, respectively, are moved back and forth with respect to one another so as to allow the entry of a form between the belts whereupon the belts are pressed together and, as they rotate, will strip the glove from the form and carry it until it emerges between the small rollers 11 and 17. The gloves travelling between the belts are ironed by means of irons 19 and 20 engaging opposite surfaces of belts 8 and 9 forming one leg of the V.

The operating mechanism is substantially like the one illustrated in my first-mentioned patent and, therefore, only so much of it is shown in Figs. 1 and 2 as is necessary for an understanding of the invention. Part 21 is a motor driven shaft mounted within the frame 15 of Fig. 1. Shaft 21 drives through suitable gearing (not shown) the large rollers 18 and 12, and the rotation of the rollers is transmitted to the small rollers 10 and 16 by means of two endless driving belts 23 and 24 encircling the two pairs of rollers. The belt 8 is placed on top of the belt 23, the two belts being held in position by means of a guide 25. Similarly, the belt 9 is placed on top of the belt 24 and the belts are held in position by means of guide 26.

The roller 10 is supported by a frame 21, rotatably mounted on shaft 22 of roller 12. Roller 16 is on a frame 28, which is oscillatable about shaft 21. Limited relative movement between the rollers 10 and 12 is insured by means of a spring 29 to permit slight relative displacement of these rollers when a glove passes between them.

A cyclic reciprocating movement between the two rollers 10 and 16 is controlled by the means fully disclosed in my first-mentioned patent.

A cam (not shown) actuates levers (not shown) to control the machine and cam 30 (Fig. 1), provided on the shaft 21, actuates a pivoted lever 31 which through a rod 32 and suitable gearing 33 provided within a housing 34 on the table 7 causes the cyclic rotation of the shaft 4. Thus it will be insured that the left hand portions of belts 8 and 9 forming one leg of the V along which they contact, will separate to allow the insertion of a form between them and will then be pressed together to strip the glove from the form and move the glove to the delivery point past the rollers 11 and 17.

The arrangement of the belts 8 and 9 is such that the gloves mounted on the forms will be definitely gripped in succession as they are moved between the belts without deforming the gloves. The glove will then be removed from the form and will be carried between the belts and the rollers 12 and 18, which will strip and flatten them.

Each of the forms 1, 1a and 1b, consists of two parts and encloses two resistances (not shown) so distributed within the form as to heat and thus dry the glove placed thereon.

Electrical contact is made with the terminals of a form as an incident of the mounting thereof on the spider 2. This feature is described in Patent 2,324,673 and includes conductors 35, 36, 37 electrically connected to a contact spring assembly.

The ends of conductors 35, 36 and 37, are connected to commutators 38, 39 and 40 (Fig. 1), respectively, mounted on the end of shaft 4, but insulated therefrom and from one another. These commutators are engaged by spring-

pressed brushes 41, 42 and 43, the whole assembly being enclosed within a housing 44 (Fig. 1), provided on table 7. On this housing 44, are mounted switches 45 and 46, by means of which the resistance elements within the irons 19 and 20 may be controlled, as well as switches (not shown) by means of which the elements within the forms may be controlled.

Crank 48 is attached at one end to shaft 21 through sleeve 47; crank 48 also engages, with its other end, sleeve link 50 through ball and socket joint 49; link 50 is engaged through a second ball and socket joint 51 with lever 52 and produces, when driven by crank 48, an oscillatory movement of shaft 53 and lever 52 attached thereto. The lower end of shaft 53 is mounted in bearing 54 supported by cross strip 56 which, in turn, is attached to two cross bars of which one is shown at 57. The upper end of shaft 53 passes through bearing 55 mounted underneath table 7.

Shaft 53 carries on its upper end and above table 7 a sleeve 58 which supports a finger pressing mechanism. The finger pressing mechanism is rotated in a surface inclined by a certain angle with respect to a horizontal plane. Shaft 4 and the fingers of forms 1, 1a, 1b, 1c, when in operative position, point in a direction having a similar angle with respect to a horizontal plane. In this way the operative movement of the finger pressing mechanism caused by the rotation of shaft 53 about a vertical axis is caused to occur in a plane substantially perpendicular to the plane in which the fingers are arranged and substantially parallel to the direction of the fingers. An accurate straightening of the finger seams is assured.

As more clearly shown in Figs. 3 and 4, the finger pressing mechanism comprises three metal blades 59 mounted on projections 60 of sleeve 58. A bolt 61 passing through holes in blades 59 and projections 60 serves to hold blades 59 in such a way as to permit a rotating movement of each blade about bolt 61. Sleeve 58 and projections 60 are made of one piece and consist of rather solid and good heat-conducting material such as aluminum casting. Blades 59 are elastic, preferably of phosphor bronze.

Riveted or welded to each of the metal blades 59 is a bronze or metal casting 62 which is formed with a projecting lug 63. Each lug 63 has a hole for receiving a screw 64. This screw is fastened in a corresponding recess 65 formed in sleeve 58. A spring 66 slipped over screw 64 and acting between lug 63 and recess 65 resiliently opposes the rotation of blades 59 on bolt 61.

Thus, the pressure exerted by the finger pressing mechanism during its rotating movement about vertical shaft 53 is made flexible. Additional flexibility is achieved by the manner in which the pressure elements engaging the glove fingers or seams are mounted.

These pressure elements as shown in Figs. 3 and 4 consist of conically profiled rollers 67 arranged in pairs on each side of each of the bronze blades 59. Rollers 67 consist of metal and are each mounted on a crank lever 68. The levers 68 are rotatably supported on the bronze blades 59 by means of pivot pins 69. Each roller 67 is attached to one end of a crank lever 68. The other end of crank lever 68 is attached to a spring 70, the free end of which is fastened to bronze blade 59 at 71. Thus it is assured that during a pressing operation each roller 67 rolls along each corner or seam of a glove finger independently from the other roller. Yielding pressure is

exerted against the seams and accurate pressing operations are performed. The correct sequence of these finger pressing operations with respect to other operations of the machine is assured by sleeve link 50. This link including ball and socket joints 49 and 51 represents the connection between the driving and the driven members of the finger pressing mechanism and is illustrated in more detail in Fig. 5.

Each ball and socket joint consists of a screw member 72 one end of which contains a thread which is attached to the driven and driving cranks, respectively. The head of screw member 72 forms the joint and is located in a corresponding recess of part 73. This part is attached to link portion 74 by means of screw 75 in an easily detachable manner. Flexibility is accomplished by spring 76 which is pressed against the inside of part 74; the tension of the spring can be varied by adjusting nut 77.

Fig. 6 shows perspective, and schematically, the various operational phases of a finger pressing mechanism such as illustrated in Figs. 1-5.

In Fig. 6, X1, X2, X3 and X4 represent the axes on which the four glove forms, only two of which, 1' and 1a', are shown, are mounted. The regular pyramid or spider formed by axes X1-X4 is rotatable about axis Y1. In this way each of the axes X1-X4 can be moved in succession into operative position such as is shown in Fig. 6 for axis X2.

Axis X1 is shown to be arranged in plane Y1, Y2 and Y3. Axis X2 falls in plane Y1, Y4 and Y5 which is perpendicular to plane Y1, Y2 and Y3 and which forms, as may be seen more clearly from Fig. 1, an acute angle U1 with the table 7.

The finger pressing mechanism is represented schematically in Fig. 6 by bronze blades 59' attached to sleeve 58'. Shaft 53' supports sleeve 58' and rotates the finger pressing mechanism about vertical axis 21. Bronze blades 59' form an angle U2 (Fig. 1) with axis Z1. This angle is slightly less than 90°. By rotating bronze blades 59' about axis Z1, the blades describe a conical surface or a number of parallel conical surfaces with the bronze blades or parts thereof forming the generatrices of the cones.

In the course of this movement, the phosphor bronze blades start from position 59'', (indicated in dotted lines in Fig. 6) and stop in operative position 59'. In the latter position the bronze blades form an angle of approximately 90° with axis X2 and the direction of the fingers or finger seams. In this position, blades 59' are substantially perpendicular to the plane in which glove form 1a' is situated. The plane in which a bronze blade 59' is situated and in which it moves immediately before and immediately after having arrived in its operative position is a tangential plane to a cone formed by the rotary movement of bronze blades 59' about axis Z1. This tangential plane is substantially perpendicular to the plane in which form 1a' is situated.

Many other solutions will occur to those mechanically minded to cause the finger pressing mechanism, at least near its operative position, to move in a plane substantially perpendicular to the plane in which the glove form or glove is situated.

It would be possible, without exceeding the scope of this invention, to arrange axis Z1 substantially perpendicular to bronze blades 59' so that during their rotation about axis Z1, bronze blades 59' describe parallel planes instead of cones. In order to achieve this, axis Z1 will have

to be arranged at an angle with respect to the vertical.

In order to facilitate the connection of axis Z1 to the driving mechanism of the entire machine, axis Z1 has been arranged vertically, and angle U2 (Fig. 1), between axis Z1 and bronze blades, has been made less than 90°. Simultaneously with axis X2 moving into operative position, as indicated in Fig. 6, stop plate 85'' is moved from the position shown in dotted lines in Fig. 6 into the full drawn position shown at 85'. This movement is a rotation about axis Z2 and is accomplished by means of hub 83' which is connected through arm 81' to stop plate 85'.

Fig. 7 shows a finger pressing machine in which one or several stationary glove forms are arranged. Each of these forms cooperates with a finger ironing mechanism in accordance with this invention.

In Fig. 7, 92 is a glove form capable of receiving a glove to be pressed. A top view of the glove form is shown in Fig. 8 and Fig. 9 shows a cross section of the form along lines 9-9 of Fig. 7. Form 92 has a base 93 which is attached to table 94 by means of screws 95.

Form 92 consists of two parts, 92' and 92''. Part 92' is stationary on base portion 93' and 92'' is hinged on base portion 93' by means of a horizontal bolt 96. Glove form 92 contains electric heater elements 97' and 97'' located in portion 92' and 92'', respectively. In order to remove or replace one of the heater elements 97', 97'' it is only necessary to separate portion 92'' from portion 92', and move it into the position shown in dotted lines in Fig. 7 against the force of spring 98.

The finger pressing mechanism consists of a device somewhat similar to that shown in Figs. 1-6. Three parallel bronze blades 99 are rotatably mounted in a vertical plane on a shaft 100. Bronze blades 99 carry independently mounted rollers 101 which are pressed by springs 102 against the seams of the glove fingers in a manner similar to that shown in Figs. 1-5.

Bronze blades 99 are rotated from the position shown in solid lines into that shown in dotted lines at 99' by means of a lever arm 103 and against the force of springs 104; lever arm 103 in turn engages at one end the free end of bronze blades 99 and is engaged at the other end by lever 105. Lever 105 is rotatable about axis 106 and mounted on the bottom side of table 94.

Lever 105 is engaged at a point intermediate its length and relatively close to axis 106 by a vertical rod 107, which has attached thereto a flange 108. This flange 108 engages the marginal portions of a slot 109 in lever 105 through which rod 107 is passed. By moving rod 107 upward in vertical direction, rod 107 with its flange 108 engages lever 105 and forces it from the position shown in dotted lines at 105' upward into the operating position drawn in full lines (Fig. 7). This movement forces lever 103 upward and pushes bronze blades 99 from position 99' down

into its operative position, shown in full lines in Fig. 7. During this movement, springs 104, which are attached with one end to bronze blades 99 and with the other end to bracket 110, are compressed.

As soon as the force exerted by rod 107, through flange 108 on lever 105, is released, compression springs 104 expand and force bronze blades 99 upward into the position shown in dotted lines at 99'.

At the same time, lever 103 is forced down and

in turn forces lever 105 into the position shown in dotted lines at 105'. The entire machine is ready for a new finger pressing operation.

Bracket 110, which carries shaft 100, is attached to table 94 by means of screws 111.

Vertical rod 107, which produces the force necessary to move bronze blades 99 into operative position, may be driven by an appropriate means without exceeding the scope of this invention, manually, semi-automatically or fully automatically, electrically, by air or liquid pressure.

In Fig. 7, rod 107 is driven by the armature or plunger (not shown) of a solenoid 112, which is attached to the bottom of table 94 by means of bolts 114, or in any other suitable manner. The energization of solenoid 112 pushes rod 107 up into the direction of arrow A, against the force of spring 113 arranged in the bottom portion of form 92. Spring 113 presses against a wedge 114' arranged slidably between portions 92' and 92''. In the course of the upward movement of rod 107, wedge 114' is pressed in a flexible manner between portions 92' and 92''. As a result, portions 92' and 92'' separate and stretch the glove mounted thereupon.

As soon as the energization of solenoid 112 ceases, rod 107 falls back under its own weight taking spring 113 and wedge 114' with it. Thus, it is possible for blades 99, lever 103 and lever 105 to return into their original positions under the force of the expanding springs 104.

In this way, positive movements of all the members associated with the finger pressing mechanism are assured.

The driving mechanism for rod 107 may be arranged in any desired manner, and in particular, may be common to a number of vertical rods (not shown) which extend into the interior of a number of parallel glove forms in a manner similar to that shown in Fig. 7. Each glove form is provided with a separate ironing device similar to that shown at 99. The various finger pressing mechanisms for these various glove forms may be arranged on a common shaft 100, and be driven through a common shaft 115. In this case, it is not necessary to provide for each triplet of bronze blades, a separate lever 103, a separate lever 105 and a separate driving rod 107. Common shaft 115 may be driven by a single lever mechanism consisting of single levers 103, 105 and rod 107, driven by a single solenoid, air valve or any other suitable driving mechanism, without exceeding the scope of this invention.

In this way a number of gloves may be simultaneously ironed under the control of a single drive mechanism and with a minimum of interconnecting links.

Ball and socket joint 49 can be disassembled by removing screw 78. The second ball and socket joint 51 is somewhat similar to joint 49 except that its insert 78 is rigidly attached to sleeve link 50 by means of a thread which adjustably fits into a corresponding thread of link 50.

Joint 51 is held in place in a similar manner as joint 49 except that the corresponding fastening screw 79 is permanently adjusted by means of a cotter splint 80 passing through screw 79 and insert 78.

In this way the effective length of sleeve link 50 and the flexibility of the connections 73, 74, 75, 76 can be adjusted independently of one another. The rotation of shaft 53 under the control of sleeve link 50 and crank 48 also controls the

movement of a stop arm which helps to back a glove form while it is in its operative position and prevent a glove being pulled from the form by rollers 67.

This stop arm, designated at 81, is rotatably mounted on shaft 82 which is supported by bearing 83 in table 7. Stop arm 81 is attached at one end to the upper end of shaft 82. On its other end, stop arm 82 carries a plate 85 which is rotatable about pivot 84. The lower end of shaft 82 has attached thereto a wheel 86 which is driven by a chain 87. One end of this chain is attached to the free end of lever 88, which is attached to and driven by shaft 53. The opposite end 89 of chain 87, after passing through wheel 86, is attached to a spring 90 which is secured to table 7 at 91.

In this way, in accordance with the movement of shaft 53, wheel 86, shaft 82 and stop arm 81 are moved and thereby stop plate 85 is pressed in a flexible manner against that glove form (1a in Fig. 2) which is in operative position.

What I claim is:

1. In a machine for ironing gloves, means for supporting the fingers of the gloves to extend substantially in a predetermined plane, seam pressing members operative for insertion at least partially between the fingers, and means for moving said pressing members while inserted in a plane substantially perpendicular to said predetermined plane.

2. In a machine for ironing gloves having seamed fingers, at least one glove form supporting the fingers of the glove to point substantially in a predetermined direction, pressing members operative for insertion at least partially between the fingers, and means for moving said pressing members while inserted in a direction substantially parallel to that of the fingers to smooth the seams of the fingers.

3. A machine according to claim 1, wherein said supporting means comprises at least one heated glove form mounted with the fingers pointing vertically upward and extending substantially in a vertical plane, and in which the pressing members are arranged rotatable about a horizontal axis extending substantially parallel to said vertical plane.

4. A machine according to claim 1, wherein the pressing members comprise a number of parallel blades facing one another and spaced in accordance with the space between the fingers of the glove, and means for moving said blades to be inserted at least partially between the fingers, said blades being formed to extend while inserted in a plane substantially perpendicular to the plane in which the fingers of the glove are arranged.

5. A machine according to claim 1, wherein the pressing members comprise a number of parallel blades facing one another and spaced in accordance with the space between the fingers of the glove, each of said blades supporting on both sides thereof pressure elements formed to engage adjacent finger sides, and means for moving said blades to be inserted at least partially between the fingers, each of said blades being formed to extend while inserted in a plane substantially perpendicular to the plane in which the fingers of the glove are arranged.

6. A machine according to claim 1, wherein the pressing members comprise a number of elastic blades facing one another and spaced in accordance with the space between the fingers of the glove, each of said blades supporting on

both sides thereof a pair of spaced spring mounted pressure rollers of conical profile to engage therebetween adjacent finger sides, and means for moving said blades to be inserted at least partially between fingers, each of said blades being formed to extend while inserted in a plane substantially perpendicular to the plane in which the fingers of the glove are arranged.

7. A machine according to claim 1, wherein the pressing members comprise a number of parallel blades consisting of spring metal and facing one another and spaced in accordance with the space between the fingers of the glove, each of said blades supporting on both sides thereof pressure elements of good heat conducting metal formed to engage adjacent finger sides, and means for moving said blades to be inserted at least partially between the fingers, each of said blades being formed to extend while inserted in a plane substantially perpendicular to the plane in which the fingers of the glove are arranged.

8. In a machine according to claim 1, wherein said supporting means comprises a heated metal glove form mounted with the fingers pointing vertically upward and extending substantially in a predetermined vertical plane, and wherein the glove form consists of two half portions, at least one of which is arranged hinged about a horizontal axis so as to permit separation, a vertical shaft on which the pressing members are mounted near one end thereof so as to be rotated in vertical planes substantially perpendicular to said predetermined vertical plane, good heat conducting pressure elements supported near the other end of the pressing members and formed to engage adjacent finger sides, means for pendulating said pressing members about said shaft, including links engaging said one end to rotate said pressing members into operative position so as to insert the pressure elements between the fingers, and springs attached to said pressing members and deformed by the rotation for moving the pressing members out of operative position.

9. A machine according to claim 1, wherein said supporting means comprises a number of heated metal glove forms supported on a spider structure, a rotary shaft within said structure and arranged symmetrically with respect to the glove forms, means for rotating said shaft intermittently to move each of said glove forms successively into operative position, each glove form when in operative position being arranged to extend the fingers of the glove substantially in a direction perpendicular to the movement of the pressing members while inserted, and pressing members consisting of a number of parallel metal blades facing one another and spaced in accordance with the space between the fingers of the glove, each of said blades supporting on both sides good heat conducting pressure elements formed to engage adjacent finger sides, said metal blades while inserted extending in a plane substantially perpendicular to the plane in which the fingers of the glove are arranged, and means for moving said blades for insertion at least partially between the fingers at a predetermined time following the movement of a glove form into operative position.

10. A machine according to claim 1, comprising means for moving the glove supporting means intermittently to place a glove form into opera-

tive position, means for moving the pressing members into operative position, and means for coordinating the movements of the glove supporting means and the pressing members.

5 11. A machine according to claim 1, comprising means for moving the glove supporting means intermittently to place a glove form into operative position, means for moving the pressing members into operative position, means for coordinating the movements of the glove supporting means and pressing members, and an additional member backing the glove form while said form is in operative position, and means for moving said additional member into operative position at a predetermined time following the placing of the glove form.

10 12. In a machine for ironing the fingers of gloves, a number of glove forms arranged on a spider structure, a first shaft secured to said spider structure, the angles between the shaft and forms being less than 90°, means for rotating said shaft intermittently to move said glove forms into operative position, each glove form when in operative position supporting the fingers of the glove in a vertical plane, a number of parallel metal blades facing one another and spaced in accordance with the space between the fingers of the glove, pressure elements supported near one end of said metal blades and formed to engage adjacent finger seams, said one end of the blades penetrating between the fingers to form an angle of 90° with the axis of the glove form, a second vertical shaft supporting said metal blades near the other end, means for rotating said second shaft to move said pressure elements into and out of operative positions, and means for coordinating the rotations of the two shafts.

15 13. A machine according to claim 1, wherein said supporting means comprises a plurality of heated glove supporting forms supported by a spider structure, a rotary shaft secured to the spider structure and disposed symmetrically to the forms, means for rotating said shaft intermittently to move said glove forms one after another into operative position, each glove form when in operative position supporting the fingers of the glove to extend substantially in a direction perpendicular to the movement of the pressing members while inserted.

20 14. A machine according to claim 12, wherein the means for coordinating the rotations comprise a common drive shaft connected to said first shaft by cam means and to said second shaft by crank means.

25 15. The device according to claim 12 and spring means disposed between each of said metal blades and said second vertical shaft.

30 16. The device according to claim 12 and a resilient adjustable connection between said second shaft and the means for rotating it, including an adjustable sleeve link and a spring in said link.

35 17. The device according to claim 12 and spring means disposed between each of said metal blades and said second vertical shaft, and a resilient adjustable connection between said second shaft and the means for rotating it, including an adjustable sleeve link and a spring in said link.

TEOBALDO G. BOLDIZZONI.
